UNITED STATES PATENT OFFICE

ARTHUR VON FRANKENBERG, OF NEW YORK, N. Y.

DESIGN FOR A COMBINED LAMP AND SUPPORTING BASE

Application filed May 9, 1931. Serial No. 39,798. Term of patent 3½ years.

To all whom it may concern:

Be it known that I, ARTHUR VON FRANKENBERG, a citizen of the United States of America, and a resident of New York city, in the county and State of New York, have invented a new, original, and ornamental Design for a Combined Lamp and Supporting Base, of which the following is a specification, reference being had to the accompanying drawing, forming part hereof.

The figure is a perspective view of my new design serving as a base for a lamp. It is also adapted to serve as a base for smoker's or other similar articles.

I claim:

The ornamental design for a combined lamp and supporting base, as described and shown.

ARTHUR VON FRANKENBERG.
